UNITED STATES PATENT OFFICE.

JOHN W. BESELL, OF HOBOKEN, NEW JERSEY.

DESIGN FOR A RAILING.

SPECIFICATION forming part of Design No. 17,702, dated September 13, 1887.

Application filed August 3, 1887. Serial No. 246,068. Term of patent 7 years.

To all whom it may concern:

Be it known that I, JOHN W. BESELL, a citizen of the United States, residing at Hoboken, in the county of Hudson and State of New Jersey, have invented and produced a new and original Design for Railings Adapted for Stairs and other Situations, of which the following is a specification, reference being had to the accompanying drawing, forming a part thereof.

The drawing is a side view of my railing adapted to apply on stairs.

In my design the railing is divided into short lengths longitudinally, and each section or length is formed in three panels, one above another. I will show the design as applied for stair railing having an ordinary inclination.

Referring to the drawing and to the letters of reference marked thereon, A A are posts extending up and down, which may be of rectangular section. These divide the railing into short lengths. They are connected at the top and bottom by straight bars M M.

B B are horizontal bars, which may be also of rectangular section, and C C C are twisted bars extending up and down and connecting the bars B B. They are evenly spaced, as shown.

D E are reversed volute scrolls. One is mounted in the upper panel above the bars B B. The other is mounted in the lower panel below the bars B B.

D' E' are subordinate scrolls applied as

branches of the main scrolls D E. One end, D, of each main scroll is larger than the opposite end, E.

My design may be employed with any required variations in the inclination of the bars M M, according as the stairs or other object on which the railing is applied may vary in inclinations. The effect on the eye is that of three panels, the central one rectangular and divided by the twisted upright bars C into smaller rectangles, and the top and bottom having a scroll and branches of the character shown, accommodating the inclination of the bars M.

I have described my design as applied to railing for stairs; but it will be understood that it may be applied to crestings, window-guards, &c.

I claim—

The design for railing herein shown and described, the same consisting of the central panel formed with vertical twisted bars C and horizontal bars B, a top panel inclosing a scroll, D, with branches D', and side bars, A A, and top and bottom bars, M M.

In testimony whereof I have hereunto set my hand, at Hoboken, in the State of New Jersey, this 2d day of August, in the presence of two subscribing witnesses.

JOHN W. BESELL.
